UNITED STATES PATENT OFFICE.

THEODOR SOETBEER, OF NEW YORK, N. Y.

CAR-STARTER.

SPECIFICATION forming part of Letters Patent No. 274,399, dated March 20, 1883.

Application filed January 9, 1883. (No model.)

To all whom it may concern:

Be it known that I, THEODOR SOETBEER, of the city, county, and State of New York, have invented a new and Improved Car-STARTER, of which the following is a full, clear, and exact description.

The object of this invention is to devise means, more especially intended for use on street-cars, whereby the force required to stop the car may be stored up and used in starting the car.

Reference is to be had to the accompanying drawings, forming part of this specification, in which similar letters of reference indicate corresponding parts in all the figures.

Figure 1 is a plan view of the bottom of a street-car having my invention applied to one of the axles thereof. Fig. 2 is a detailed elevation of the axle and pinion, showing the starting and stopping racks in transverse section; and Fig. 3 is a plan view of the starting and stopping racks.

A represents the spring. B represents the pinion, placed loosely upon the square axle C. D represents the stopping and E the starting rack, attached at their rear ends to one end of the spring A; and F F' represent cams for shifting the pinion for stopping, locking, and starting the car. These cams are operated by the connecting-rods G G, attached to them and to the cog-wheel H, which is adapted to be turned in either direction by the pinion J, attached to the vertical brake-rod K, as will be understood from Fig. 1.

It is designed to provide both axles of the car with starting devices, and for this purpose I make the spring A S-shaped, so that both of its ends may be utilized, requiring but a single spring for both sets of starting devices; and I attach the spring A to the bottom L of the car by means of the staples a a.

The pinion B is made with the reduced portion b, larger portion b', and reduced plain portion b².

The stopping and starting racks are attached together at their ends, as shown at f f, and are pivoted to the end of the spring A by the pivot g, and the starting-rack E has rack-teeth only for a short distance, as shown at h in Fig. 3, and passes over or above the axle C and rests in contact (except as hereinafter described) with the larger portion b' of the pinion

B. The stopping-rack D has teeth nearly its whole length, as shown at h', passes under the axle C, and is held up in contact (except as 55 hereinafter described) with the reduced portion b of the pinion by the guide-staples d d. The starting-rack E also passes through these guide-staples, which serve to hold the racks firmly and securely in place.

The operation of the device is as follows: When the car is in motion the pinion B will have been shoved along upon the axle C by the cam F', so that the reduced portion b of the pinion will stand to one side of the stopping-rack D, as shown in Fig. 1, and the spring A will have moved the racks D E forward until the teeth h of the starting-rack E will stand in front of the teeth of the larger portion b' of the pinion, leaving the plain portion of the 70 rack E resting upon the larger portion b' of the pinion. In this position it will be seen that the racks E D in no manner interfere with the free revolution of the axle C or the movement of the car in either direction. When it is desired to stop the car the brake-rod K will be turned so as to cause the cam F to shove the pinion on the axle C to the position shown in Fig. 2, in which position the pinion will stand to one side of the starting-rack and the teeth 80 of the reduced portion b will engage the teeth of the stopping-rack D, and thus the forward movement of the car will cause the rack D (carrying the rack E with it) to be moved forcibly back against the spring A, causing it to 85 be compressed and to act as a brake to the axle and car. The car having come to a full stop, the brake-rod K will be turned so as to cause the cam F' to shove the pinion B to a position intermediate between the positions 90 shown in Figs. 1 and 2, in which position the teeth of the reduced portion b will still engage the teeth of the rack D, and the teeth of the larger portion b' will engage the teeth h of the rack E, which will lock the spring A in its compressed state and hold the car at rest. Now,

to start the car the rod K will be turned still farther to cause the cam F' to shove the pinion B along on the axle C until the teeth of the reduced portion b disengage the teeth of the 100 stopping-rack D, whereupon the force of the spring A will force the racks forward, and this force will be applied through the starting-rack E to the upper side of the pinion B, causing

it to turn the axle C, and thus assist in the starting of the car.

Instead of using the cams F F' for shifting the pinion B, other means might be devised and not depart from the spirit of my invention, and to avoid any difficulty of the teeth of the pinion registering with the teeth of the racks when the pinion is shoved to either side, the teeth might be slightly beveled off at the ends, so that there will be no danger of the pinion coming to a dead stop against the teeth of either rack.

The object in making the pinion B with the reduced portion *b* and larger portion *b'* is so that the backward movement of the racks will not be too rapid, and so that the force of the spring A will be augmented in the starting of the car.

Having thus described my invention, I claim as new and desire to secure by Letters Patent—

1. In a car-starter, the wheel H, adapted to be rotated by any suitable means, the rods G G, end pivoted to opposite sides of said wheel, and the pivoted cams F F', in combination with a slide-pinion, B, whereby said pinion will

be alternately moved in opposite directions, as described.

2. In a car-starter, the loose shifting-pinion B, having the large spur portion *b'*, the small spur portion *b*, and the plain portion *b²*, and the end connected bars, D E, having respectively the opposite long and short racks *h h*, in combination with axle C, whereby the actuating-spring may be made to operate in either or in neither direction according to the position of the wheel, as described.

3. The racks D E, pivoted to the spring A, in combination with the pinion B, cams F F', rods G G, wheels H and J, and vertical shaft K, as and for the purposes set forth.

4. The rack D, having the teeth *h'*, extending its whole length or nearly its whole length, and the rack E, having the teeth *h*, extending only a portion of its length, in combination with the pinion B, adapted to slide upon the axle C, as and for the purposes set forth.

THEODOR SOETBEER.
